United States Patent Office

Des. 222,606
Patented Nov. 16, 1971

222,606

JUG

Gordon A. Strand, Toledo, Ohio, assignor to
Owens-Illinois, Inc., Toledo, Ohio

Filed Dec. 4, 1970, Ser. No. 26,291

Term of patent 14 years

Int. Cl. D9—01

U.S. Cl. D9—40

FIG. 1

Des. 222,606

PAGE 2

FIG. 2

FIG. 5

FIG. 3

FIG. 4

FIG. 1 is a perspective view of a jug showing my new design;

FIG. 2 is an elevational view, the opposite side being a mirror image of the side shown;

FIG. 3 is an elevational view taken from the right of FIG. 2;

FIG. 4 is an elevational view taken from the left of FIG. 2; and

FIG. 5 is a top plan view.

I claim:

The ornamental design for a jug, substantially as shown and described.
